UNITED STATES PATENT OFFICE

WALTER S. VIELE, OF NEW YORK, N. Y., ASSIGNOR TO AMERICAN MAIZE-PRODUCTS COMPANY, A CORPORATION OF MAINE

DESIGN FOR A JUG

Application filed February 7, 1931. Serial No. 38,584. Term of patent 7 years.

To all whom it may concern:

Be it known that I, WALTER S. VIELE, a citizen of the United States, residing at 130 East 40th Street, New York city, New York, have invented a new, original, and ornamental Design for a Jug, of which the following is a specification, reference being had to the accompanying drawings, forming part thereof.

Fig. 1 is a plan view of a jug of transparent material showing my new design; Fig. 2 is a side view thereof, and Fig. 3 is another side view thereof taken at right angles to Fig. 2.

I claim:
The ornamental design for a jug, as shown and described.

WALTER S. VIELE.
